The ornamentals design for a video camera with adjustable legs, as shown and described.

DESCRIPTION

FIG. 1 is a perspective view of a video camera with adjustable legs showing my new design in a folded position; FIG. 2 is a perspective view thereof in an upright position; FIG. 3 is a top plan view thereof in the upright position; FIG. 4 is a front elevational view thereof in the upright position;

FIG. 5 is a right side elevational view, the left side elevational view being a mirror image thereof in the upright position;

FIG. 6 is a rear elevational view thereof in the upright position; and,

FIG. 7 is a bottom plan view thereof in the upright position.
